BALLAST WORKING IMPLEMENT AND
METHODPeter P. Jargick, West Chicago, Ill., assignor to
Electric Tamper & Equipment Company, Lud-
ington, Mich.

Application January 9, 1935, Serial No. 969

2 Claims. (Cl. 104—13)

The main objects of this invention are:

First, to provide a ballast working tool which is especially well adapted for loosening the ballast between and under railway ties.

Second, to provide means in an implement of this character for preventing the ballast stones from wedging between the picks thereof.

Third, to provide a new method and means for cleaning and servicing ballast by vibrations of high frequency.

Fourth, to provide a ballast working tool which is of very large capacity and highly efficient for the purpose intended and at the same time is easy to operate.

Fifth, to provide a novel and improved method of loosening or bleeding the ballast between railway ties.

Objects relating to details and economies of my invention will appear from the description to follow. The invention is defined and pointed out in the claims.

A structure which is a preferred embodiment of my invention is illustrated in the accompanying drawing, in which:

Fig. 1 is a fragmentary perspective view of a ballast working implement embodying features of my invention in operative relation to the ballast of a railway.

Fig. 2 is an enlarged fragmentary view in side elevation of the implement, parts being shown in vertical section.

Fig. 3 is an enlarged view in front elevation of the tool proper.

Fig. 4 is an enlarged transverse vertical section taken on a line corresponding to line 4—4 of Fig. 3.

Referring to the drawing, 1 indicates the ballast for the cross ties 2 of a railway, one rail of which is shown at 3. Where crushed rock ballast is employed, the voids between the rocks gradually fill with fine material such as clay, cinders, coal dust and the like, and as moisture accumulates forms binder which very tightly binds together the crushed rocks. Therefore, when a tie is to be renewed, the first operation is to pick this packed ballast loose on each side of the tie as well as at the ends, cutting an opening through what is termed the shoulder of the ballast. It is also found necessary at certain times to loosen the ballast between and under the railway ties to insure proper drainage of water. In the past, this has been done mainly by means of hand picks, a very laborious and expensive operation, and sometimes expensive screening steps are employed. I aim to provide a method and machine

by means of which the ballast can be more efficiently and effectively loosened and screened or freed from the fine dirt that has accumulated.

To this end, I provide a ballast working implement 4 comprising a handle 5, a vibrating motor 6, a blade-like tool holder or shank 7, and a fork-like tool 8. The handle consists of a pair of spaced bars 9 connected by cross pieces 10 and 11, the handle bar or grip 12 being secured between the upper ends of the bars 9. The handle 10 carries a support member 13 of flexible material having one end looped around the cross piece 11 and the other end looped around the cross piece 14 carried by the slide 15. The slide is provided with outwardly facing channel portions 17 embracing the bars 9, the slide being adapted to be adjusted by means of a bolt 18 arranged through the cross member 10 to tension the support member 13.

The motor 6 has a housing 19 provided with attaching ears 20 which are secured to the support member 13 by means of clamps 21, these clamps and the clamping bolts 22 thereof engaging the ends of the strap constituting the support member 13, as shown. The shaft 23 of the motor has an eccentric or unbalancing weight 24 thereon so that during the rotation thereof high frequency vibrations are imparted to the blade 7 and fork 8. The flexible support member 13 provides a shock or vibration absorbing means 30 for the handle bar 12 without materially decreasing the efficiency of the implement.

The tool holder blade or bar 7 is rigidly attached to the end of the housing 19 opposite the support member 13 by means of bolts 25 extending through the ears 26 of the housing. The holder 7 is thus clamped in place between the flat plates 27 and 28. The holder 7 is preferably of resilient material to increase the effectiveness of the device in operation.

To the lower end of the holder 7, I mount the tool 8 by means of the rivets 29, the tool being of substantial thickness and having spaced picks, tines, or prongs 30 for coaction with the ballast 1. To prevent the stones in the ballast from wedging between the picks 30, the outer ends of the latter are flared at 31 so that their inner ends are spaced farther apart than their outer ends. The prongs of the tool are thus made self-cleaning. The working ends of the picks or prongs 50 are preferably sharpened as shown by Fig. 4. In operation, the prongs of the tool constitute a plurality of picks which are rapidly vibrated from the vibratory device. In renewing old or defective ties, renewal gangs equipped with my 55

implements are able to perform four times more work than when equipped with old-fashioned picks.

When the ballast becomes foul or filled with binding or filling substances and hardens, it ceases to perform its function as a means of draining excess water, and water pockets are formed beneath the ties. Each time a train passes over the tie, it is depressed and pumps the water and mud to increase the pockets under the tie, resulting in time in a very rough, uneven track. To correct this situation, my implements are utilized in loosening the ballast at the tie ends and beneath the ties to a sufficient depth to drain the water. This operation is termed "bleeding" the ties and is a very important factor in the maintenance of rock ballasted railways in coal hauling territory. With my implements, this operation may be performed eight 20 times faster than with old-fashioned picks. The implements are highly useful and efficient where complete cleaning of the ballast is desired.

The high frequency vibration of the prongs of the tool automatically sifts the cinders and small particles through the rock ballast to a point below the bottom of the ballast section, thus making the usual forking and screening operations unnecessary in most cases.

I have illustrated and described my improve-

ments in an embodiment which I have found very practical. I have not attempted to illustrate or describe other embodiments or adaptations as it is believed this disclosure will enable those skilled in the art to embody or adapt my 5 improvements as may be desired.

Although I have shown and described a certain specific embodiment of my invention, I am fully aware that modifications thereof are possible. My invention is therefore not to be restricted except insofar as is necessitated by the prior art and by the spirit of the appended 10 claims.

Having thus described my invention, what I claim as new and desire to secure by Letters Pat- 15 ent, is:

1. In a ballast working implement of the character set forth, a tool comprising a yoke having a plurality of spaced prongs projecting therefrom, the ends of said prongs being sharpened and 20 flared laterally toward each other to prevent the wedging of ballast stones therebetween in operation.

2. In a ballast working implement of the character set forth, a tool comprising a yoke having 25 a plurality of spaced prongs projecting therefrom, the ends of said prongs being flared laterally toward each other.

PETER P. JARGICK.
